UNITED STATES PATENT OFFICE

2,621,930

POWER-ACTUATED PIN-SETTING APPARATUS

Theodore E. Mead, Wilmette, Ill.

Application May 8, 1948, Serial No. 25,856

3 Claims. (Cl. 273—42)

1

This invention relates to power actuated pin setting apparatus for use in connection with bowling alleys for the accurate and ready setting or spotting of pins.

An object of the invention is to provide apparatus for use in the game of ten pins, the apparatus providing pressure fluid means for rapidly moving the pin setting carriage to pin setting position on the alley. Yet another object is to provide pressure fluid mechanism for moving the pin setting carriage against the force of spring means to pin setting position, the springs being effective, upon the release of the pressure fluid, for returning the pin setting carriage to elevated position. Another object is to provide simple mechanism which may be adjustably supported upon the guide rod housings or guide tubes of the pin setting apparatus for supporting a pressure fluid cylinder in a position for engagement with the carriage and for moving the carriage to pin setting position, etc. A still further object is to provide bracket means adapted to be secured to the housing or guide tubes of pin setting apparatus and equipped with inwardly-extending arms, the inner ends of the arms being connected for engagement with a fluid pressure cylinder device for producing vertical movement of the carriage. Other specific objects and advantages will appear as the specification proceeds.

The invention is illustrated, in a single embodiment, by the accompanying drawing, in which—

Figure 1 is a broken perspective view of apparatus embodying my invention; Fig. 2, a top plan view of the pressure fluid mechanism employed for moving the pin setting carriage; Fig. 3, a broken vertical sectional view of the fluid pressure cylinder and associated parts; Fig. 4, a side view in elevation, the pin setting carriage being shown in elevated position; Fig. 5, a view similar to Fig. 4 but showing the carriage in a lower position adjacent the alley; and Fig. 6, a perspective view of a form of valve apparatus which may be employed in connection with the invention.

In the illustration given, 10 designates the alley upon which the pins are to be placed. The alley is provided with the usual side walls 10^a. The pin setting apparatus shown in the drawing is well known in the art and need not be described herein in detail. On each side of the alley is secured a frame support 11 provided with a brace 12. Hollow cross bars 13 and 14 are secured upon plates 15 carried by the members 11.

2

Guide tubes 16 provide housings for the guide rods 16^a, which are fixed at the lower ends to the pin setting carriage 17. The pin setting carriage is equipped with the usual recesses 18 for receiving the pins to be placed or spotted on the alley and with the usual mechanism for uprighting the pins in the selected spots upon the alley 10 when the carriage is moved downwardly into pin setting position.

10 The carriage is normally urged toward elevated position by the pivotally-mounted arms 19 and 20, which are equipped at their outer ends with tie rods 21 that extend downwardly and are connected to the carriage. At their inner ends, the arms 19 and 20 are connected by levers with springs 22 and 23 housed within the frame tubes 13 and 14, the action of the springs serving to maintain the levers 19 and 20, as is well known, in their elevated position, and thus holding the carriage 17 by means of the tie rods 21 in the raised position illustrated in Fig. 1.

25 The carriage 17 is equipped with a handle rod 24 mounted upon the pivot arms 25 and to which are connected link arms 26 extending downwardly and fixed to the carriage 17. Since such structure is commonly used and well known in the art, a detailed description is believed unnecessary herein.

30 In the operation of the pin setting apparatus manually, the operator grasps the handle 24 and presses it downwardly so as to swing the carriage 17 into a position just above the alley. The usual members are provided for engaging the alley and for setting the pins in vertical position. Such downward movement is made against the force of the springs 22 and 23, and upon the release of the handle 24, the springs return the arms 19 and 20 to the position shown in Fig. 1, and such arms lift through the connecting links 21 the pin setting carriage 17 to the elevated position shown in Figs. 1 and 2.

35 The manual operation described is extremely tiresome, taxing the strength of the pin boy to the utmost, and often toward the end of the working period, resulting in improperly set pins. As time progresses, the pin boy tends to become slower in the pin setting operation, and the owner and the players lose considerable time in the use of the alleys.

40 In the specific illustration given, I provide simple power mechanism for effectively operating the pin setting apparatus, the pressure being applied to the handle 24 at the central portion thereof, and quick action, both in the setting op-

eration and release operation, is effected through the use of a simple pressure fluid control valve.

Upon each of the housing tubes 16 is secured an arm 27 by means of a clamping collar 28, the arms extending inwardly and upwardly and meeting at a substantially central point. The ends of the arms are united by bolts or other means to provide a plate 29. Pivots mounted upon the plate 29 is a compressed air cylinder 30 having a piston 31 and a piston stem 32 secured to the piston, as shown more clearly in Fig. 3. The lower end of the piston stem 32 is provided with a recess 33 receiving the members 34 and 35 held within the recess by a pin 36. The members 34 and 35 are spread outwardly to provide diverging arms receiving the handle 24. The members 34 and 35 are preferably elongated, as shown more clearly in Fig. 1, so as to engage a substantial portion of the handle 24 near the center of the handle, and thus to distribute the load or impact over a relatively wide area of the handle. The arms 34 and 35 are secured upon the handle 24 by bolts 37, or by other suitable means.

The lower end of the cylinder 30 is closed by a threaded closure plug 38 having a vent 39 therein. To cushion the upward movement of the piston stem, I provide a compression spring 40 bearing at its upper end against a closure 38 and resting at its lower end upon a washer 41 around the piston stem 32. The upper end of the cylinder is closed by a threaded head 42 having an inlet passage 43 equipped with a nipple 44 for receiving a flexible tube 45 leading to a fluid pressure control valve 46.

The control valve 46 may be supported at any convenient position. In the illustration given, it is supported upon one of the guide tubes or housings 16. It will be understood that any suitable type of valve may be employed. In the illustration given, the valve 46 is equipped with an intake nozzle 47 connected to any source of pressure fluid and with an outlet nozzle 48 connected to tube 45.

The valve casing is provided with the usual vent or outlet 49. The valve plunger or stem 50 is actuated by a handle 51 pivotally supported upon the bracket 52.

The pins upon the bowling alley 10 are indicated in the drawing by the numeral 53.

The sloping position of the cylinder causes a binding action on the piston stem 32 as it passes through closure plug 38 when the piston is in the extended or "down" position. I have found that this difficulty can be overcome while still using relatively thin cylinder walls by securing a guide ring 54 to the piston rod 32, as shown more clearly in Fig. 3, and at a distance well below the piston 31. In the specific illustration given, the piston rod 32 is provided with roughening or with longitudinal ridges 55, and the guide ring 54 is effectively anchored upon these ridges by forcing the ring thereon to the position shown in Fig. 3. The ring 54 engages the cylinder wall 30 at some distance from the piston 31, and the condition which formerly resulted in a binding action, is now reduced to such an extent that smooth sliding action is secured at all points of the stroke.

Operation

In the operation of the apparatus, the carriage 17 is normally in the elevated position illustrated in Fig. 1, the spring-loaded arms 19 and 20 serving to maintain the carriage 17 in this position.

When it is desired to reset the pins 53 at their proper positions upon the alley 10, the fallen pins are placed within the openings 18 of the carriage 17, and the valve handle 51 is depressed to direct pressure fluid through outlet 48 and tube 45 to the upper end of the cylinder 30. The pressure fluid at the top of the cylinder presses the piston rod 32 downwardly, transmitting the force against the yoke formed by the members 34 and 35 about handle 24. The handle 24 is depressed, and by means of the links 26, the carriage 17 is swung downwardly to pin setting position. As the carriage 17 approaches the floor, the engagement of members with the floor uprights the pins in their proper positions, and the carriage is now ready to be retracted. Upon the release of handle 51, the spring-urged plunger 50 moves upwardly, closing off the inlet pipe 47 and connecting the conduit 45 with the exhaust port 49. The compressed air is released, and the carriage returns under its spring pressure to its normal elevated position.

By employing a single pressure cylinder 30 and the bracket means described for supporting it centrally with respect to the handle 24, I find that a balanced operation takes place, with the pin setting apparatus moving smoothly and evenly to either limit of its movement. The fixed guide tubes or housing members 16 support, through the inclined arms 27, the pressure cylinder 30 in the central position shown and enable it to function evenly by exerting pressure upon the central portion of the handle 24.

While, in the foregoing specification, I have set forth a specific construction in considerable detail for the purpose of illustrating one embodiment of my invention, it will be understood that such details of structure and form may be varied widely by those skilled in the art without departing from the spirit of my invention.

I claim:

1. In pin setting apparatus equipped with vertically-extending guides, a pin setting carriage mounted on said guides for vertical movement, arm-equipped clamps secured to the upper portion of said guides, said arms extending inwardly and joined at their inner ends, a piston-equipped cylinder pivotally mounted in an inclined position upon the said arm ends, a stem fixed to said piston and connected to said carriage, and means for supplying pressure fluid to said cylinder to move said piston relative to said cylinder.

2. In pin setting apparatus, a frame providing spaced vertical guides, a pin setting carriage mounted upon said guides for vertical movement, arms fixed to the upper end portions of said guides and extending inwardly toward each other, a pressure cylinder pivotally connected to said arms in an inclined position and provided with a piston, a piston rod connected to said piston at its upper end and at its lower end connected to said carriage, means for admitting pressure fluid into said pressure cylinder to move said piston, and a guide ring connected to said piston rod at a spaced distance from said piston and slideably engaging the inner wall of said cylinder.

3. Power-actuated apparatus for use with a pin-setting machine having stationary vertical guides, a carriage guided thereby for vertical movement, and a handle member fixed to the carriage, comprising a pair of arms adapted to be fixed to said guides and extending inwardly toward each other to provide a suspension member, a power device comprising a pressure cyl-

inder provided with a piston and a piston rod, connecting means pivotally connecting said suspension member with one of the elements of said power device, said power device being supported thereby in an inclined position, and means for admitting pressure fluid into said pressure cylinder to move said piston, said piston rod being provided with a guide ring connected to said piston rod at a spaced distance from said piston and slidably engaging the inner wall of said cylinder.
